PROCESS FOR CRACKING HYDROCARBON OILS AND PRODUCING ETHYLENE

Original Filed Sept. 3, 1926

UNITED STATES PATENT OFFICE

1,962,198

PROCESS FOR CRACKING HYDROCARBON OILS AND PRODUCING ETHYLENE

Lyman C. Huff, Chicago, Ill., assignor to Universal Oil Products Company, Chicago, Ill., a corporation of South Dakota

Continuation of application Serial No. 133,467, September 3, 1926. This application September 14, 1931, Serial No. 562,747

5 Claims. (Cl. 260—170)

This application is a continuation of my application Serial No. 133,467, filed September 3, 1926.

My invention relates to an improved process for cracking hydrocarbon oils and one in which 5 ethylene may be produced as an incident to the practice of the process. It has heretofore been the practice to subject heavy hydrocarbons to cracking either in the liquid phase, the vapor phase or a combined liquid and vapor phase process for the purpose of producing lighter hydrocarbons. My invention relates to a combined liquid phase and vapor phase process and contemplates an improvement in what is known in the art as a continuous process.

15 More specifically, my invention contemplates the superheating of vapors from which the heavier constituents have been removed by condensation and the subjection of such vapors to further reaction whereby a more efficient cracking operation is effected and substantial quantities of ethylene produced. The invention particularly contemplates the subjection of a hydrocarbon oil to cracking conditions, the dephlegmation of vapors evolved from the oil, the superheating of the 25 dephlegmated vapors, the further reaction of the superheated vapors and the recovery of the final products resulting from such further reaction of the superheated vapors.

In the drawing there is diagrammatically 30 shown in side elevation an apparatus suitable for practicing the invention.

For the purposes of clearness the operation of the process will be described in connection with the apparatus illustrated in the drawing. It is to be understood, however, that other forms of apparatus may be employed.

The apparatus comprises generally a furnace A, oil heating coil B, a vapor superheating coil C, a primary reaction chamber D, preferably unheated for the heated oil, a primary dephlegmator E for the vapors issuing from the chamber D, a secondary reaction chamber F, preferably unheated for the superheated vapors from the coil C, a secondary dephlegmator G in which vapors 45 issuing from the chamber F are treated, a final condenser H and a receiver I.

In operation the oil is supplied to the coil B through the line 1, pump 2 and charging line 3. The oil may be either directly passed to the coil 50 B or by suitably controlling the valves 4, 5, 7 and 9 the oil or a portion thereof may be passed through the line 6 and either passed through the closed conduit 8 in the dephlegmator G or through the by-passing line 10 controlled by the valve 9 55 to the line 11 and thence delivered to the primary

dephlegmator E through the spray 12, or by suitably regulating the valves 13 and 14 the oil flowing through the line 11 may be passed through the closed conduit 15 disposed within the primary dephlegmator E and thence passed by way of the 60 line 16 and valve 17 to the charging line 3.

It will be understood that when oil is delivered to the primary dephlegmator E through the spray 12, the unvaporized portions of this oil together with reflux condensate separated from the vapors 65 in the dephlegmator E will be passed via the line 18 and valve 19 to the charging line 3. In the event that differential pressures are employed, or in the event that the gravity head of the liquid is insufficient to supply the same to the charging 70 line 3, the charging oil and reflux oil from the dephlegmator E may be, by suitably controlling valves 19, 20 and 21 forced under a mechanical pressure imposed by the pump 22 into the charging 75 line 3.

The oil passed through the heating coil B is raised to a cracking temperature therein and is then delivered by way of the line 23 controlled by the valve 24 to the primary reaction chamber D wherein substantial conversion of the oil and 80 vaporization thereof takes place. Unvaporized residue accumulating in the chamber D can be withdrawn therefrom through the lines 25 controlled by the valves 26. The vapors issuing from the chamber D are caused to pass through the 85 line 27 controlled by the valve 28 to the primary dephlegmator E wherein the heavier or insufficiently cracked fractions of the vapors are condensed forming reflux condensate which accumulates in the bottom of the dephlegmator E, and 90 is removed therefrom through the line 18 as above described.

The uncondensed vapors leave the dephlegmator E through the line 29 controlled by the valve 30 and in the preferred operation of the process these 95 vapors are passed via the line 32 controlled by the valve 31 to the vapor superheating coil C positioned in the furnace A. It is to be noted that this coil C is nested intermediate the upper and lower rows of the tubes forming the coil B. This permits of the imparting of a moderate or tempered heat to the vapor superheating coil C. The superheated vapors from the coil C are conveyed through the line 33 controlled by the valve 34 to the secondary reaction chamber F wherein the 105 superheated vapors undergo additional reaction or conversion. For the purpose of accelerating the flow of the vapors through the coil C and also for preventing carbon formation therein, steam may be supplied to the line 32 through the line 35 con- 110

trolled by the valve 36. Steam may also be introduced through the line 35 at the end of a run for the purpose of aiding in the cleaning of the coil C. Furthermore steam may be passed through the 5 coil C to prevent burning out of this coil in the event that it is not employed for superheating oil vapors.

Any heavy hydrocarbons resulting from the 10 superheating and reaction of the vapors will accumulate in the secondary reaction chamber F and may, if in liquid form, be removed therefrom through the lines 37 controlled by the valves 38. The vaporous products leave the secondary reaction chamber through the line 39 controlled by the 15 valve 40 and may be passed through a suitable heat interchanger 41 positioned in the bottom of the secondary dephlegmator G which functions as a reboiler for condensate collecting in the bottom of the secondary dephlegmator G. The vapors from the heat interchanger 41 pass through the 20 line 42 into the dephlegmator G. In the event that it is not desired to subject the vapors issuing from the secondary reaction chamber F to additional dephlegmation these vapors may be passed 25 directly to the condenser H through the line 43 controlled by the valve 44. When, however, the vapors are delivered to the dephlegmator G they pass therefrom through the line 45 controlled by the 30 valve 46 to the final condenser H from which the distillate and gases flow through the line 47 controlled by suitable valve 47' to the receiver I which is of conventional form being provided with a valve controlled distillate drawoff line 48 and a valve controlled gas outlet line 49. A sec- 35 ondary distillate drawoff line 50 controlled by valve 51 is provided which communicates with the pump 52 by which distillate collecting in the receiver I may be forced via the line 53 controlled by the valve 54 into the top of the secondary dephlegmator G. By closing the valve 54 and opening the valve 55, this distillate may be passed 40 through the line 56 and united with reflux condensate from the secondary dephlegmator in the line 60, these substances being charged by the pump 57 and line 58 to the primary dephlegmator E where they are introduced through the spray 59. The reflux condensate from the secondary dephlegmator which is withdrawn from the line 60 45 may be passed to the primary dephlegmator E as above described, or wholly or in part withdrawn from the process and sent to suitable storage through the line 62 by suitably controlling valves 61 and 63.

It may be desirable at some times to eliminate 55 the vapor treating system from the process and to directly condense the vapors issuing from the primary dephlegmator E. To permit of such an operation I provide the line 64 controlled by the valve 65 for conveying vapors issuing from the primary dephlegmator E through the line 29 to the final condenser H. It will be understood, of course, that when these vapors are being passed to the final condenser H, the valve 31 in the line 60 65 32 will be closed. While the superheating of vapors evolved in the cracking operation has been suggested, it has never heretofore provided practical because of the abundance of carbon present in the vapors which is separated therefrom and collects as a flint like coating on the walls of the vapor superheating zone. It will be seen that in my process all of the heavier constituents which 70 contain the greatest percentage of carbon are separated from the vapors prior to the superheating of the vapor, and that I thereby eliminate the 75 difficulties due to excessive carbon formation. I

furthermore provide a time element for the reaction of the superheated vapors by introducing these vapors to the enlarged reaction chamber F.

The process may be carried out by maintaining uniform pressure conditions throughout all of the 80 separate zones thereof. However, it is desirable to maintain a somewhat lower pressure on the vapor treating portion of the system, that is the heating coil C, reaction chamber F and associated elements, than is maintained in the oil treating portion of the system. One particular advantage obtained from such an operation is that the pressure maintained in the oil treating system is sufficient to convey the vapors through the vapor treating portion of the system. It is to be noted, 85 however, that the introduction of steam through the line 35 enables the operation of the process when uniform pressures are maintained. It will be understood that the ethylene produced by the process will be taken off from the receiver I with 90 the gases and recovered therefrom.

Because of the variations in the character of hydrocarbon oils of different characteristics and from different sources, the operating conditions maintained in the process must necessarily be varied and to this end the process is extremely flexible. Good results may be obtained, however, 100 when treating a fuel oil by subjecting the same in the coil B to a temperature of from 800 to 850° F., and by maintaining a pressure in the 105 liquid treating portion of the system of from 135 to 150 pounds per square inch.

Heating of the vapors in the coil C can be controlled by various means. For example, the rate of cooling in the dephlegmator E will, of course, 110 govern the quantity of vapor passed through the coil C as well as the quantity of oil flowing through the coil B. By suitably controlling the temperature in the dephlegmator E, the desired superheating of the vapors in the coil C can be 115 obtained. The degree of heat imparted to these vapors will, of course, be dependent upon the character of the oil treated and the character of the product obtained. A skilled operator can by observing the characteristics of the distillate and 120 gases produced determine the best operating temperature for the vapors from a particular oil and by suitably controlling the conditions of the dephlegmator maintain such temperature.

From the foregoing, it will be seen that I have 125 devised an improved continuous process for the cracking of hydrocarbon oil and the production of ethylene which may be incorporated in many of the existing continuous cracking processes without substantial change in the present instal- 130 lation.

What I claim as my invention is:

1. A process for cracking heavy hydrocarbon oil and for producing ethylene which comprises subjecting the oil to cracking conditions of tem- 135 perature and pressure and separating the same into vapors and residue, dephlegmating the vapors to condense heavier and insufficiently cracked fractions thereof while retaining the normally condensable light cracked products in vapor 140 form, returning resultant reflux condensate to the cracking step for retreatment in the process, heating such light cracked products uncondensed by said dephlegmation to an ethylene-producing 145 temperature while in vapor phase, cooling the thus heated vapors to condense normally liquid constituents thereof, and separating the resultant condensate from the ethylene-containing gases.

2. A process for cracking heavy hydrocarbon oil and for producing ethylene which comprises 150

- subjecting the oil to cracking conditions of temperature and pressure and separating the same into vapors and residue, dephlegmating the vapors to condense heavier and insufficiently cracked fractions thereof while retaining the normally condensable light cracked products in vapor form, returning resultant reflux condensate to the cracking step for retreatment in the process, heating the dephlegmated vapors, prior to condensation thereof, and reacting the same at an ethylene-producing temperature in admixture with steam, cooling the thus heated vapors to condense normally liquid constituents thereof, and separating the resultant condensate from the ethylene-containing gases. 80
3. A process for cracking heavy hydrocarbon oil and for producing ethylene which comprises subjecting the oil to cracking conditions of temperature and pressure and separating the same into vapors and residue, dephlegmating the vapors to condense heavier and insufficiently cracked fractions thereof and returning resultant reflux condensate to the cracking step for retreatment in the process, heating the dephlegmated vapors, prior to condensation thereof, and reacting the same at an ethylene-producing temperature, dephlegmating the thus heated vapors independently of the first-mentioned vapors thereby forming secondary reflux condensate, introducing such secondary reflux condensate into contact with said first-mentioned vapors undergoing dephlegmation to assist the dephlegmation thereof and returning unvaporized portions of the secondary reflux condensate to the cracking step in admixture with the first-mentioned reflux condensate, further cooling the still uncondensed vapors to condense normally liquid constituents thereof, and separating the ethylene-containing gases from the resultant condensate. 90
4. A hydrocarbon oil cracking process which comprises subjecting the oil to cracking conditions of temperature and pressure in a cracking zone, removing evolved vapors and dephlegmating the same in a primary dephlegmating zone to condense heavier fractions thereof as primary reflux condensate, passing the dephlegmated vapors to a vapor phase conversion zone and treating the same therein at an ethylene-producing temperature under lower pressure than is maintained on the oil in the cracking zone, dephlegmating the thus treated vapors in a second dephlegmating zone thereby forming secondary reflux condensate, combining at least a portion of said secondary reflux condensate with the primary reflux condensate and supplying the resultant mixture under pressure to the cracking zone, cooling the vapor-gas mixture from the second dephlegmating zone to condense normally liquid constituents thereof, and separating the ethylene-containing gases from the resultant condensate. 95
5. A hydrocarbon oil cracking process which comprises subjecting the oil to cracking conditions of temperature and pressure in a cracking zone, removing evolved vapors and dephlegmating the same in a primary dephlegmating zone to condense heavier fractions thereof as primary reflux condensate while retaining the normally condensable light cracked products in vapor form, passing light cracked products uncondensed by said dephlegmation to a vapor phase conversion zone and heating the same therein at an ethylene-producing temperature under lower pressure than is maintained on the oil in the cracking zone, dephlegmating the vapors from said vapor phase conversion zone in a second dephlegmating zone thereby forming secondary reflux condensate, combining at least a portion of said secondary reflux condensate with the primary reflux condensate and supplying the resultant mixture under pressure to the cracking zone, cooling the vapor-gas mixture from the second dephlegmating zone to condense normally liquid constituents thereof, and separating the ethylene-containing gases from the resultant condensate. 100
10. 4. A hydrocarbon oil cracking process which comprises subjecting the oil to cracking conditions of temperature and pressure in a cracking zone, removing evolved vapors and dephlegmating 105
